George W. Sharp ATTORNEY

UNITED STATES PATENT OFFICE.

SYLVESTER V. OSBURN, OF COFFEYVILLE, KANSAS.

TANK-CAR.

1,264,327.

Specification of Letters Patent. Patented Apr. 30, 1918.

Application filed November 5, 1917. Serial No. 200,462.

To all whom it may concern:

Be it known that I, SYLVESTER V. OSBURN, a citizen of the United States, residing at Coffeyville, in the county of Montgomery 5 and State of Kansas, have invented certain new and useful Improvements in Tank-Cars, of which the following is a specification.

This invention relates to tank cars, and more especially to tank cars for the trans- 10 portation of liquids, and the primary object of the invention is to produce a tank car in which the shocks of coupling and end collisions are more equitably distributed over the entire structure than with cars of standard 15 type.

A further object is to produce a tank car of such construction that where a series of them are coupled together, the car receiving the impact direct transmits a greater pro- 20 portion of the shock to the adjacent car, and the latter to the next car and so on, than occurs with cars of standard type, this distribution of the strain serving to relieve 25 and guard against injury of the car receiv- ing the direct impact.

More specifically my object is to provide a tank car in which shocks of the character mentioned, are imposed yieldingly on the tank and thence transmitted to both trucks 30 as distinguished from the standard type in which the shock on the trucks is cushioned only by the draft gear or rigging at the end of the car where the impact occurs, it being obvious that through this construction, any 35 resiliency in the tank proper as well as the contents thereof, is utilized in further minimizing the effect of the shock on the trucks.

Another object is to provide a construction wherein all parts are readily accessible 40 for the purpose of repair and the renewal of worn parts, thereby reducing the difficulties and dangers encountered at present in making repairs to tank cars as heretofore constructed.

A still further object is to produce a tank car possessing the features of advantage hereinbefore set forth, at less cost of manufacture than those of approved design now in use.

With these objects in view the invention 50 consists in certain novel and peculiar features of construction and combinations of parts as hereinafter described and claimed; and in order that it may be fully understood

reference is to be had to the accompanying 55 drawings, in which:

Figure 1, is a fragmentary side view of a tank car embodying my invention.

Fig. 2, is an enlarged vertical section taken through the central portion of the car. 60

Fig. 3, is a fragmentary view partly in side elevation and partly in central vertical longitudinal section, said figure being shown on a scale larger than that of Fig. 1, but smaller than that of Fig. 2. 65

Fig. 4, is a horizontal section taken on the line IV—IV of Fig. 3, but showing an element of the structure lying below said plane, partly in horizontal section.

Fig. 5, is a fragmentary end view of the 70 car, with an element thereof broken away.

Fig. 6, is a detail perspective view of the lower part of one of the cradle braces of the car.

In the said drawings, 1 indicates the cus- 75 tomary cylindrical tank of a tank car, the same as is usual, overlying the truck bolsters 2, only one of which are shown (see Fig. 5), and each truck bolster is provided centrally with a circular socket 3, and near each end 80 with a bearing lug 4.

Vertically above each truck bolster is a cradle frame, each of said frames comprising an upper member 5 and a lower member 6, and said members vertically above the 85 centers of the truck bolsters conjointly form openings 7, shown in this instance as a circular opening, the lower ends of the central portion of member 5 terminating in outwardly projecting ears 8 and the upper ends 90 of member 6 in outwardly projecting ears 9 bolted to ears 8. Each lower member is provided with a horizontal base 10 provided with a depending pivot boss 11 engaging the socket 3 of the underlying bolster so that the 95 latter may be free to turn as the truck rounds a curve. Each truck is provided with a fixed pin 12 projecting upward centrally through the pivot boss 11 of the adjacent member 6 of the bracket. The upper mem- 100 ber of each of said brackets conforms to and fits flatly against the lower part of the tank and is riveted thereto as at 13, and is pro- vided with V-shaped brace arms 14 extending

divergently downward at opposite sides 105 of the central portion, and terminating in close proximity to the bearing lugs 4 of the truck bolster. The said braces are spaced

slightly from said bearing lugs so as to provide for slight lateral flexure in the car and to minimize torsion strains, and are tied to member 6 by braces 15.

- 5 The brackets described constitute cradle braces and are generically identified herein-after by said term, their special function as suggested being to guard against sidewise movement or rolling of the car on the trucks 10 but without eliminating flexing action entirely.

Interposed between the tank and bolsters and extending parallel to the former, is a sliding member, shown in this instance as a 15 longitudinal pipe or tube 16, said sliding member extending through the openings 7 formed in the cradle braces and being capable of slidable action therein, and said member is prevented from turning around its 20 own axis through the provision of longitudinal slots 17 receiving the pins 12 of the bolsters.

The slideable member midway its length is provided with a longitudinal slot 18, and secured to and within said member at opposite sides of the vertical plane of said slot are thrust plates 19 stiffened by longitudinally extending ribs 20, there being two sets of said plates spaced apart equal distances from a point midway the length of said slot, and said plates are provided at their lower inner or adjacent corners with horizontal flanges or shelves 21 underlying a pair of follower plates 22 pressed apart by 35 an interposed cushion or spring 23, the inner ends of the said plates 19 normally determining the position of said follower plates, and in this connection it will be understood that the flanges or shelves 21 form temporary supports for the follower plates to uphold them in convenient position for engagement by the spring, the pressure of the latter being sufficient to hold them substantially centrally of the sliding member when 45 the parts are in operative relation.

To transmit power from the member 16 when the same moves endwise, a pair of abutment lugs 24 depend through the slot 18 outward of the follower plates, from a 50 segmental plate 25 riveted to the lower central portion of the tank, said lugs respectively receiving the thrust yieldingly transmitted from the slideable member through the cushion or spring 23. The mechanism 55 comprised by the parts 19 to 25 inclusive, constitutes a shock absorbing device. The sliding member is adapted to carry car coupler members 26 shown in fragmentary form only at one end of Fig. 1, as said coupling 60 members may be of any approved type, and it is also proposed to employ any suitable draft rigging, not shown, to absorb the ordinary shock incident to the coupling of the cars. The draft rigging may be of any preferred type, such for instance as that known 65

as the Cardwell gear, it being understood that if the Cardwell gear is employed as the shock absorbing device at the center of the car and sliding member, it will be necessary to provide the sliding member with side 70 slots 27 for the accommodation of the laterally projecting rods of such gear which are omitted as they are in general use and form no essential part of this invention.

Assuming that a car embodying the invention is coupled to another car so that the coupling shock shall move the slideable member in the direction indicated by the arrow, Fig. 1, it will be apparent that the thrust plate or plates 19 at the left hand end of slot 18 (see Fig. 3), will move the engaged follower plate 22 to the right and thereby effect compression of the spring 23 against the right hand abutment lug 24 of the tank, the shock upon the latter being thus cushioned, it being noted that in this action the right hand thrust plate 19 moves out of engagement with the thrust receiving or right hand follower plate 22, and that the thrust imposing following plate likewise 90 moves away from the adjacent or left hand abutment lug 24. The shock imposed upon the tank is evenly distributed through the same and its contents to the ends of the tank whence it is taken up by the cradle braces 95 and transmitted therefrom into the trucks with minimized force.

I have found by practical tests that the use of a slideable member to receive the impact of one car upon another and to transmit the shock to the central portion of the tank and through the latter and its contents to the trucks, minimizes wear and tear and racking strains on the truck and the connections between the same and the 100 tank, and by experiments have determined that through the combination of elements above set forth and constituting the essential features of my invention, the necessity for repairs and replacements of broken 105 parts of tank car will be infrequent.

It will be apparent that under the impact incident to the coupling of cars, the movement imparted to a slideable member will be transmitted through the draft connections to the slideable members of the adjacent cars and that consequently the strain or shock will be distributed throughout an entire series of cars but proportionately diminished as the cars of the series successively receive the shock. Because of this distribution of the shock through the slideable members, no single car will receive as great a proportionate shock as occurs with cars of standard construction.

It will be apparent that the slideable member of a car can be readily detached from the tank and trucks to give better access for purposes of repairs and replacement, but that for most repairs, such as resetting of 130

rivets and the like, there will be no necessity for disturbing the relation between the tank and said slidable member.

From the above description it will be apparent that I have produced a tank car embodying the features of advantage enumerated as desirable in the statement of the object of the invention, and while I have illustrated and described the preferred embodiment of the same, it is to be understood that it is susceptible of modification without departing from the principle of construction involved or sacrificing any of the advantages of the appended claims.

15 I claim:

1. In a tank car, the combination with a tank, underlying truck bolsters, and brackets secured to the tank and pivotally supported on said bolsters, of a member paralleling the tank and slidably carried by the said brackets, and means for causing the slidable member when slid endwise on its supports, to apply yielding pressure in the same direction on the tank.

2. In a tank car, the combination with a tank, underlying truck bolsters, and brackets secured to the tank and pivotally supported on said bolsters, of a member paralleling the tank and slidably carried by the said brackets, and means for causing the slidable member when slid endwise on its supports, to apply yielding pressure in the same direction on the tank and for returning said member to normal position after 35 the impelling power thereof is spent.

3. In a tank car, the combination with a tank, underlying truck bolsters, and brackets secured to the tank and pivotally supported on said bolsters, of a member paralleling the tank and slidably carried by the said brackets, and a spring cushion interposed between the slidable member and the tank for transmitting power from the former to the latter and reacting to return 45 the slidable member to normal position.

4. In a tank car, the combination with a tank, underlying truck bolsters, and brackets secured to the tank and pivotally supported on said bolsters, of a member paralleling the tank and slidably carried by the said brackets, spaced lugs secured to the slidable member, spaced lugs rigid with the tank, and a spring interposed between the lugs of the slidable member and also between 55 the lugs of the tank for transmitting power from either of the first-named lugs to the tank through a lug thereof, and for reacting to transmit power from such tank lug to the slidable member through a lug of the latter.

5. In a tank car, the combination with a

tank, underlying truck bolsters, and brackets secured to the tank and pivotally supported on said bolsters, of a member paralleling the tank and slidably carried by the 65 said brackets, and having a pin-and-slot connection with the bolsters, spaced lugs secured to the slidable member, spaced lugs rigid with the tank, and a spring interposed between the lugs of the slidable member and 70 also between the lugs of the tank for transmitting power from either of the first-named lugs to the tank through a lug thereof, and for reacting to transmit power from such tank lug to the slidable member through a 75 lug of the latter.

6. In a tank car, the combination of a tank, truck bolsters underlying the tank near the ends thereof, brackets bearing pivotal relations to the bolsters and rigid relations 80 with the tank, a slidable member parallel to the tank and adapted to receive endwise the impact incidental to the coupling of cars, and yielding means for transmitting shock from the sliding member to the tank.

7. In a tank car, the combination of a tank, truck bolsters underlying the tank near the ends thereof, brackets bearing pivotal relations to the bolsters and rigid relations with the tank, a slidable member parallel to the tank and adapted to receive endwise the impact incidental to the coupling of cars, and provided with a longitudinal slot and opposite thrust shoulders, a plate secured to the tank and provided with lugs 95 depending into said slot, and a resilient cushion to transmit power from the thrust shoulders to said lugs and from the latter to said shoulders.

8. In a tank car, a slidable member to 100 receive and yield to shocks incidental to the coupling or endwise abutment of cars, and means for yieldingly transmitting such shocks from said member to the body or tank about midway the length thereof.

9. In a tank car, the combination of the tank, underlying bolsters, cradle braces secured to the tank and pivotally resting on the bolsters centrally thereof, and consisting of lower members and upper members 110 secured together and conjointly forming openings, the upper members having downwardly diverging arms spaced slightly from the bolsters near the outer ends thereof, a sliding member extending through the said 115 openings of the braces, yielding means to transmit endwise movement of the sliding member to the tank, and means to prevent rotary movement of the sliding member.

In testimony whereof I affix my signature. 120

SYLVESTER V. OSBURN.
